BURNER CONTROL MECHANISM

Vilynn O. Beam, Minneapolis, Minn., assignor to
Minneapolis-Honeywell Regulator Company,
Minneapolis, Minn., a corporation of Delaware

Application July 1, 1942, Serial No. 449,259

12 Claims. (Cl. 158—117.1)

This invention is concerned with a burner control mechanism and more particularly with one adapted to be employed in a burner control system having provision for automatically igniting the burner.

An object of the present invention is to provide an improved burner control system of a type providing for a timed delivery of fuel during which combustion must take place or the system will be shut down.

An object of the present invention is to provide a burner control mechanism employing a device adapted to control the operation of a burner with a first motor for moving the device to an active position and a second timing motor for moving the device away from this active position with means responsive to the establishment of combustion for rendering the second motor inoperative in the event of the establishment of combustion.

A further object of the invention is to provide a burner control mechanism such as set forth in the preceding object in which the means for moving the burner control device away from its active position consists of an electrically heated thermal timer which is deenergized upon the establishment of a burner flame.

A still further object of the invention is to provide an arrangement of the type discussed in the preceding objects in which the energization of the second motor is initiated by movement of the first motor to a position in which said control device is in its active position.

A still further object of the present invention is to provide such an arrangement in which the burner control device is a valve whose active position is one in which fuel flow to the burner is permitted.

A still further object of the present invention is to provide such an arrangement in which the valve controls the flow of fuel to a pilot burner adapted to ignite a main burner.

A still further object of the invention is to provide such a burner control device in which burner motor means is provided for reducing the amount of fuel flow to an intermediate value, this further motor means being placed into operation upon the first motor means moving its associated valve to its open position.

A further object of the present invention is to provide such a system in which the various motors are electrically operated motors and in which the operation is initiated by a main controlling switch.

A still further object of the present invention is to provide an arrangement such as discussed

in the last paragraph in which means responsive to the pressure of the fuel being supplied to the burner is operative in the event of the pressure falling below a predetermined value to interrupt the energizing circuits to the various motor means.

Other objects of the invention will be apparent from a consideration of the accompanying specification, claims and drawing, of which the single figure is a schematic representation of my improved burner mechanism embodied in a burner control system.

Referring to the drawing, a main gas burner is indicated by the reference numeral 10. The burner 10 is supplied with gas through a pipe 11 which is connected to the outlet side of a valve 12. The inlet side of valve 12 is in turn connected to a pipe 13 which is connected to a pressure responsive device 14. The inlet side of the pressure responsive device 14 is in turn connected to a pipe 15 leading to any suitable source of gas (not shown).

Disposed adjacent the main burner 10 is a pilot burner 16. This pilot burner is supplied with gas by pipes 17 and 18, the latter of which is connected to pipe 13 on the inlet side of valve 12. Thus, the flow of gas to pilot burner 16 is independent of valve 12. A valve 19 is connected between pipes 17 and 18 to control the flow of gas to burner 16. Located in igniting relation to pilot burner 16 is a flare burner 20. This flare burner is connected by a pipe 23 to the outlet side of a valve 21 which in turn is connected through piping 22 to pipe 17 on the outlet side of valve 19. Thus, the flow of gas to burner 20 is controlled by both valves 19 and 21.

The valve 12, previously referred to, may be operated by an electromagnetic actuator of any conventional type. As shown in the drawing, the actuator is a solenoid actuator comprising a core 25 and a winding 26. Upon energization of the winding 26, the core 25 is drawn upwardly to move the valve 12 to open position. Associated with the valve core 25 is a switch blade 27 adapted to cooperate with a fixed contact 28. When the core 25 moves up to move the valve 12 to open position, the switch blade 27 is moved into engagement with contact 28.

Referring now to valve 19, this valve is adapted to be controlled by a pair of thermal motors 31 and 32 which together constitute a motor means for controlling the position of valve 19. The motor 31 is designed to cause opening of valve 19 while the motor 32 is designed to close it. The motor 31 comprises a bimetallic element 37 which is secured at its left-hand end to a fixed

support 34. Associated with the bimetallic element is an electrical heater 35. As indicated by the arrow disposed adjacent the right-hand end of bimetallic element 33, the element is adapted to warp upwardly upon being heated. The motor 32 comprises a bimetallic element 37 and a heater 38. The bimetallic element 37 is fixed at its left-hand end to a fixed support 39. As indicated by the arrow adjacent the right-hand end of element 37, this element is adapted to warp downwardly upon being heated.

Projecting from the valve 19 is a valve stem 41 which is secured to the valve disk of the valve. The valve disk of valve 19 is biased to open position so that stem 41 tends to move upwardly. When in its cold condition, the bimetallic element 37 will permit such upward movement. The upward movement is, however, resisted by bimetallic element 33 which bears against the rod 42 interposed between the two bimetallic elements. Thus, when both bimetallic elements 33 and 37 are unheated, the bimetallic element 37 tends to assume an uppermost position such as to permit valve 19 to open but is prevented from assuming this position by the bimetallic element 33 acting through the spacing rod 42 between the two elements. Obviously, as soon as the heater 35 is energized, bimetallic element 33 warps upwardly so as to permit valve 19 to move to open position. Whenever heater element 38 is energized, on the other hand, bimetallic element 37 no longer tends to assume its uppermost position but is slowly moved downwardly to the position shown in the drawing in which position the valve 19 is closed. Thus, the effect of the motor 31, upon being energized, is to cause opening of valve 19 while the effect of motor 32, upon being energized, is to cause closing of valve 19.

Bimetallic element 33 not only operates to control the position of valve 19 but it also operates a pair of contacts 44 and 45 adapted to engage with contacts 46 and 47, respectively. Upon heater 35 being energized to cause movement of bimetallic element 33 upwardly to cause opening of valve 19, the contact 45 is moved into engagement with contact 47. Upon further heating, further upward movement of bimetallic element 33 is resisted so that the element warps downwardly at its middle to move contact 44 out of engagement with contact 46. Thus, upon continued heating of bimetallic element 33, contact 45 is first engaged with contact 47 and then contact 44 is separated from contact 46.

Referring now to the valve 21, a thermal motor 50 is provided for actuating this valve. This motor comprises a bimetallic element 51 secured at its left-hand end to a fixed support 55 and an electrical heater 53 disposed in heating relation with the bimetallic element 51. The bimetallic element 51 bears at its right-hand end against a valve stem 52 secured to the movable valve element of the valve 21. The valve 21 is biased to open position and normally assumes this position when the bimetallic element 51 is unheated, this position being the one shown in the drawing. As indicated by the arrow adjacent the right-hand end of bimetallic element 51, this element warps downwardly upon being heated. Thus upon heater 53 being energized so as to cause heating of bimetallic element 51, the right-hand end of bimetallic element 51 moves downwardly to cause closure of valve 21.

A hot wire igniter 54 is provided for igniting the gas issuing from the flare burner 20. This igniter consists of a wire element adapted to be

heated to incandescence by the passage of current therethrough.

A pilot burner combustion switch is generally indicated by the reference numeral 56. This switch comprises a bimetallic element 57 disposed adjacent to the flame of pilot burner 16. A link extends between the free end of the bimetallic element 57 and a switch blade 59. Switch blade 59 is adapted to be moved between contacts 60 and 61. As indicated by the arrows adjacent bimetallic element 57, the upper end of the element moves to the right upon being heated, and towards the left upon cooling. As a result, when the burner flame is extinguished so that the bimetallic element is unheated, switch blade 59 occupies the position shown in which it is in engagement with contact 60. When, on the other hand, the bimetallic element 57 is heated by reason of being exposed to a pilot burner flame, the switch blade 59 occupies a position in which it is in engagement with contact 61. Thus contact 60 may be referred to as the "cold" contact and contact 61 the "hot" contact.

A thermostat 65 is illustratively shown as the main controlling switch. This thermostat is of conventional construction and comprises a bimetallic element 66 to which are secured a pair of contact blades 67 and 68. These contact blades are adapted to engage with fixed contacts 69 and 70, respectively. As indicated by the legends adjacent the thermostat, the bimetallic element 66 is so arranged that upon a temperature drop, contact blades 67 and 68 are moved to the right into engagement with contacts 69 and 70. Switch blade 68 is more widely spaced from contact 70 than is switch blade 67 from contact 69, so that upon such a temperature drop, contact blade 67 is first moved into engagement with contact 69 and thereafter upon a further drop in temperature, contact blade 68 is moved into engagement with contact 70.

The pressure responsive device 14 was briefly referred to before. This comprises a housing 75 in which is located a diaphragm (not shown) exposed to the pressure within the fuel line. This diaphragm is in turn connected through a stem 76, to a switch blade 77 which, in turn, is adapted to engage a fixed contact 78. Under normal conditions, the diaphragm within housing 75 is continually exposed to gas pressure so that switch blade 77 is normally held in engagement with contact 78. Upon the gas pressure dropping below a predetermined value for which the regulator 14 is set, switch blade 77 is allowed to move away from engagement with contact 78. As will be pointed later, the switch blade 77 and contact 78 control the energization of the entire system.

A step-down transformer 79 is employed to supply power for the control system illustrated. This transformer comprises a line voltage primary winding 80 and a low voltage secondary winding 81. The line voltage primary winding 80 is connected to any suitable source of power (not shown).

Operation

The various elements are shown in the position occupied when the temperature to which thermostat 65 is subjected is at or above the desired value. Under these conditions, valves 12 and 19 are both closed and no gas is flowing to any of the burners.

Let it now be assumed that the temperature in the space in which thermostat 65 is located

drops to cause closure first of contact blade 67 with contact 69 and then of contact blade 68 with contact 70. Until both contact blades have engaged their respective contacts, no energizing circuit is established. However, as soon as both blades have engaged their contacts, an energizing circuit is established to the heating element 35 of motor 31 as follows: from the left-hand end of secondary 81 through conductor 84, switch blade 77, contact 78, conductor 85, conductor 86, contact 69, contact blade 67, contact blade 68, contact 70, conductors 87 and 88, heater 35 and conductors 89, 91, 92 and 93 to the right-hand terminal of secondary 81. Energization of heater 35 causes the bimetallic element 33 to be heated so as to cause the right-hand end thereof to warp upwardly permitting valve 19 to move slowly toward open position. The opening of valve 19 causes gas to flow to the pilot burner 16. Gas also flows through pipe 22, valve 21, and pipe 23 to the flare burner 20.

As soon as bimetallic element 33 has moved to a position in which valve 19 is substantially fully open, the contact 45 carried by bimetallic element 33 engages fixed contact 47 to cause the establishment of the following circuit to igniter 54: from the left-hand terminal of secondary 81 through conductor 84, switch blade 77, contact 78, conductors 85 and 95, contact 47, contact 45, bimetallic element 33, contact 44, contact 45, conductor 96, igniter element 54, and conductors 97 and 93 back to the other terminal of secondary 81. The result of the establishment of this circuit is that the igniter coil 54 is energized and rapidly heats up so as to be capable of igniting the gas issuing from flare burner 20. Under all normal conditions, the flare burner 20 is ignited and the flame therefrom in turn ignites the gas issuing from pilot burner 16.

The engagement of contact 45 with contact 47, previously referred to, also results in the establishment of the following energizing circuit to heating element 33: from the left-hand end of secondary 81 through conductor 84, switch blade 77, contact 78, conductors 85 and 95, contacts 47 and 45, bimetallic element 33, conductor 99, heating element 33, and conductors 101, 102, 91, 92 and 93 back to the other terminal of secondary 81. The establishment of this circuit causes the flare pilot valve 21 to be slowly moved towards closed position to interrupt the flow of gas to flare burner 20. The reason for this action is that it is not normally desirable to have the igniter element 54 exposed to a burner flame any longer than necessary. Continued exposure of such a hot wire igniter element to a burner flame leads to its early deterioration. By placing the igniter element in the path of a flare pilot burner flame which is terminated as soon as combustion is established, the igniter element is only subjected to a burner flame during the brief period in which ignition is taking place.

The engagement of contacts 45 and 47 also causes the establishment of an energizing circuit to heater 33 as follows: from the left-hand end of secondary winding 81, through conductor 84, switch blade 77, contact 78, conductors 85 and 95, contacts 47 and 45, bimetallic element 33, conductor 105, heater element 33, conductors 106 and 107, switch blade 59, cold contact 60, and conductors 108, 92 and 93 back to the other terminal of secondary 81. The establishment of the circuit just traced causes bimetallic element 33 to be heated so that its lower right-hand end tends to move downwardly to close valve 19. If

this action were allowed to continue long enough, valve 19 would be reclosed so as to terminate the flow of fuel to the pilot burner 16. It is to be noted, however, that the circuit just traced included the switch blade 59 and the cold contact 60. If the pilot burner is ignited as is usually the case, the bimetallic element 33 is heated so that the upper end thereof warps to the right to move switch blade 59 out of engagement with contact 60 and into engagement with contact 61. As soon as switch blade 59 moves out of engagement with contact 60, the circuit which was traced to heating coil 33 is interrupted so as to terminate further movement of bimetallic element 33 in valve closing direction. Thus, as soon as the pilot valve is opened and the igniter coil 54 is energized so as to make possible ignition of the pilot burner, the valve 19 is slowly moved towards closed position. If the pilot burner is not ignited, this movement will be allowed to continue until the valve is completely closed. If, on the other hand, the pilot burner is ignited as normally is the case, the bimetallic element 33 will be heated to cause separation of switch blade 59 from contact 60 so as to terminate energization of the motor 32 and thus to leave valve 19 in the open position. Thus a time period is provided for the establishment of combustion conditions. If combustion does not occur within this time period, the motor 32 is operative to terminate completely the delivery of fuel to the burner 16.

The continued heating of bimetallic element 33 by heater 33 after the engagement of contacts 45 and 47 tends to cause the middle portion of bimetallic element 33 to bow downwardly since upward movement of the right-hand end is no longer possible. The result of this is that contact 44 is separated from contact 46. Since these contacts 44 and 46 are in series with igniter coil 54, their separation will result in deenergization of the igniter coil. It will be noted that this does not occur until after pilot valve 19 has been opened for a substantial time and has started to reclose. Thus, the igniter coil 54 is automatically deenergized when the need for its energization is over.

The engagement of switch blade 59 with the hot contact 61 results in the establishment of the following energizing circuit to winding 26 of the operating mechanism for valve 12: from the left-hand end of secondary 81, through conductor 84, switch blade 77, contact 78, conductors 83 and 86, contact 69, contact blade 67, contact blade 68, contact 70, conductors 87 and 116, hot contact 61, switch blade 59, conductors 107 and 111, winding 26, and conductors 112, 102, 91, 92 and 93 back to the other terminal of secondary 81.

The energization of winding 26 as a result of the establishment of the circuit just traced causes solenoid core 25 to be raised to move valve 12 to open position. The opening of valve 12 permits a flow of gas to the main burner 10, this gas being ignited by the pilot burner 16. Thus as soon as the bimetallic element 33 has indicated that the pilot burner is ignited, a circuit is established to the operating mechanism for the main burner valve to admit gas to the main burner.

The energization of winding 26 with the resultant movement of solenoid core 25 to its uppermost position causes switch blade 27 to be moved into engagement with contact 28. Engagement of switch blade 27 with contact 28 results in the establishment of a new energizing circuit to wind-

ing 26 which is independent of contact blade 68 and contact 70, this circuit being as follows: from the left-hand end of secondary 81, through conductor 84, switch blade 77, contact 78, conductors 85 and 86, contact 69, contact blade 67, bimetallic element 66, conductor 115, contact 28, switch blade 27, conductor 116, winding 26, and conductors 112, 102, 91, 92 and 93 back to the other terminal of secondary 81. Since this new circuit is independent of switch blade 68 and contact 70, momentary separation of this contact blade from this contact does not cause deenergization of winding 26. In other words, as soon as winding 26 is once energized to open the valve 12, its energization is assured until the temperature has risen sufficiently to cause separation of contact blade 67 from contact 69. Thus, any tendency of the valve to chatter due to unstable engagement of the thermostat contacts is entirely avoided. While such a holding circuit was not established in connection with the various other motors traced, these other motors were all heat motors so that a momentary deenergization thereof would not cause any harmful effects. The position assumed by a heat motor is the result of a cumulative effect and the fact that it is momentarily deenergized at any time does not interfere with its operation.

Under normal conditions, the furnace will continue in operation until such time as the temperature adjacent the thermostat has risen sufficiently to cause separation of contact blade 67 from contact 69. When this happens, the energizing circuit to the main valve operating winding 26 is interrupted so as to cause closure of main valve 12. At the same time, the circuit to heating element 35 of motor 31 is deenergized so as to cause valve 19 to be closed to cut off the flow of gas to the pilot burner. The resultant extinguishment of the pilot burner causes cooling off of the bimetallic element so as to cause separation of switch blade 59 from contact 61 and movement of the switch blade into engagement with contact 60. The result of this is that it is no longer possible to energize the main valve and in order to start the system up, it is necessary to go through the cycle traced above.

It is obvious that if at any time during the operation, the pilot burner 16 is extinguished, the thermostatic element 57 cools off to cause separation of switch blade 59 from contact 61 with the result that the winding 26 is deenergized and the main burner valve 12 is closed to interrupt operation of the main burner. This is desirable inasmuch as it is usually unsafe to operate the main burner unless the pilot burner is also lighted.

If at any time, there is a failure of gas pressure, or if the gas pressure drops below a predetermined safe value, the switch blade 77 is separated from contact 78. It is to be noted that switch blade 77 is connected directly to the left-hand end of secondary 81. The result of this is that all of the circuits traced are through switch blade 77 and contact 78. Consequently, when this happens, both the main valve motor and the various pilot valve motors are completely deenergized so that the elements assume the various positions shown in the drawing. In this way, it is assured that the gas flow to the main burner will be instantly stopped as soon as the gas pressure is inadequate to support proper combustion. Furthermore, if the gas has not been turned on or if gas pressure is too low, no attempt will be made to ignite the burner.

Conclusion

It will be seen that I have provided a new burner control system employing a new and novel burner control mechanism in which provision is made for providing the conditions necessary to the establishment of combustion for a timed period during which combustion must take place before the system will be placed in such condition to require manual intervention. This, furthermore, is accomplished in an extremely simple manner with a minimum of parts.

While I have shown a specific embodiment of my invention, it is to be understood that this is only for purposes of illustration and that my invention is to be limited solely by the scope of the appended claims.

I claim as my invention:

1. In combination, a device adapted to control the operation of a burner and movable toward and away from an active position permitting burner operation, a first motor associated with said device for causing movement of the same to said active position, a second timing motor for causing movement of said device away from said active position, means dependent upon the actuation of said first motor for activating said second timing motor to exert a force urging said device toward inactive position, and means including a device responsive to the establishment of a burner flame for rendering said second motor inoperative in the event of the establishment of a burner flame.

2. In combination, a device adapted to control the operation of a burner and movable toward and away from an active position permitting burner operation, a first motor associated with said device for causing movement of the same to said active position, an electrically heated thermal timer for causing movement of said device away from said active position, and means including a device responsive to the establishment of a burner flame for deenergizing said thermal timer in the event of the establishment of a burner flame.

3. In combination, a device adapted to control the operation of a burner and movable toward and away from an active position permitting burner operation, a first motor associated with said device for causing movement of the same to said active position, a second timing motor for causing movement of said device away from said active position, means responsive to movement of said first motor to a position in which said device is in said active position to initiate operation of said second motor, and means including a device responsive to the establishment of a burner flame for rendering said second motor inoperative in the event of the establishment of a burner flame.

4. In combination, a valve adapted to control the flow of fluid fuel to a burner and movable toward and away from a fuel flow permitting position, a first motor associated with said valve for causing movement of the same towards said fuel flow permitting position, a second timing motor for causing movement of said valve away from said fuel flow permitting position, means dependent upon the operation of said first motor for causing said second motor to exert a force resisting movement of said device to flow permitting position, and means including a device responsive to the establishment of a burner flame for rendering said second motor inoperative.

5. In combination, valve means adapted to control the flow of fuel to burner means and

movable between flow preventing, minimum flow, intermediate flow, and full flow positions, means for moving said valve means to full flow position, a first motor means for causing movement of said valve means to intermediate flow position, a second motor means for causing movement of said valve means to minimum flow position, means operative upon said valve means being moved to full flow position to cause operation of both said first and second motor means, and means responsive to the establishment of a controlling condition for terminating closing operation of said second motor means.

6. In combination, a first burner, a second burner disposed in igniting relation thereto, a first valve controlling the flow of fuel to both of said burners, a second valve controlling the flow of fuel to only said second burner, motor means for causing first opening of said first valve and then closing movement of it after a timed interval, a second motor means controlled by said first motor means and operative upon said first valve being opened to close said second valve, and means responsive to the establishment of combustion to terminate closing operation of said first motor means before said first valve is closed.

7. In combination, a first burner, a second burner disposed in igniting relation thereto, an electrical igniter disposed in igniting relation to said second burner but out of the path of the flame of said first burner, a first valve controlling the flow of fuel to both of said burners, a second valve controlling the flow of fuel to said second burner, motor means for causing first opening of said first valve and then closing movement of it after a timed period, means for initiating operation of said first motor means to open said first valve, a second motor means controlled by said first motor means and operative upon said first valve being opened to close said second valve, means to cause energization of said igniter and means responsive to a combustion condition and operative in the event of the establishment of combustion to terminate closing operation of said first motor means before said first valve is closed.

8. In combination, a first burner, a second burner disposed in igniting relation thereto, an electrical igniter disposed in igniting relation to said second burner but out of the path of the flame of said first burner, a first valve controlling the flow of fuel to both of said burners, a second valve controlling the flow of fuel to said second burner, motor means for causing first opening of said first valve and then closing movement of it after a timed period, means for initiating operation of said first motor means to open said first valve, a second motor means for closing said second valve, means controlled by said first motor means for initiating operation of said second motor means and for causing energization of said electrical igniter for a time period, and means responsive to a combustion condition and operative in the event of the establishment of combustion to terminate closing operation of said first motor means before said first valve is closed.

9. In a fluid fuel burner control system, a main burner, a pilot burner, a main valve controlling the flow of fuel to the main burner, a second valve controlling the flow of fuel to the pilot burner, first motor means for operating said main valve, second motor means for operating said second valve first to open said second valve and then moving it toward closed position after a timed period, a main controlling device, means operative upon said controlling device moving to a predeter-

mined position to initiate operation of said second motor means to open said second valve, and means responsive to a combustion condition and operative in the event of the establishment of combustion to terminate closing operation of said second motor means and initiate operation of said first motor means to open said main valve.

10. In a fluid fuel burner control system, a main burner, a pilot burner, a main valve controlling the flow of fuel to the main burner, a second valve controlling the flow of fuel to the pilot burner, first electrically operated motor means for operating said main valve, second electrically operated motor means for operating said second valve first to cause said second valve to open and then to cause it to move toward closed position after a timed period, a main controlling switch, means operative upon said switch being closed to establish an energizing circuit to said second motor means to cause said second valve to open, and switching means responsive to a combustion condition and operative in the event of the establishment of combustion to cause energization of said first motor means and to effect the energization of said second motor means in such a manner as to cause the latter to maintain said second valve in open position instead of closing it.

11. In a fluid fuel burner control system, a main burner, a pilot burner, a main valve controlling the flow of fuel to the main burner, a second valve controlling the flow of fuel to the pilot burner, first electrically operated motor means for operating said main valve, second electrically operated motor means for operating said second valve first to cause said second valve to open and then to cause it to close after a timed period, means including a device responsive to a condition indicative of the need for burner operation and operative upon said condition assuming a predetermined value to establish an energizing circuit to said second motor means to cause said second valve to open, switching means responsive to a combustion condition and operative in the event of the establishment of combustion to cause energization of said first motor means and to effect the energization of said second motor means in such a manner as to cause the latter to maintain said second valve in open position, and means responsive to the pressure of the fuel being supplied to said burner and operative in the event of said pressure dropping below a predetermined value to cause deenergization of both said first and second motor means.

12. In a fluid fuel burner control system, a main burner, a pilot burner, a main valve controlling the flow of fuel to the main burner, a second valve controlling the flow of fuel to the pilot burner, first electrically operated motor means for operating said main valve, second electrically operated motor means for opening said second valve, a third electrically operated motor for closing said second valve, a main controlling switch, means operative upon said switch being closed to establish an energizing circuit to said second motor means to open said second valve, means including a switch controlled by said second motor means for establishing an energizing circuit to said third motor, and switching means responsive to a combustion condition and operative in the event of the establishment of combustion to cause energization of said first motor means to open said main valve and to interrupt the energizing circuit to said third motor.
